DESIGN FOR A PENCIL LEAD TESTING MACHINE

Carl J. Essmann, Brooklyn, N. Y.

Application October 25, 1937, Serial No. 72,404

Term of patent 3½ years

To all whom it may concern:

Be it known that I, Carl J. Essmann, a citizen of the United States and a resident of Brooklyn, in the county of Kings and State of New York, have invented a new, original, and ornamental Design for a Pencil Lead Testing Machine, of which the following is a specification, reference being had to the accompanying drawings, forming part thereof.

Figure 1 is a front elevation of a pencil lead testing machine showing my new design.

Figure 2 is a top plan view thereof, and

Figure 3 is a side elevational view of the machine.

I claim:

The ornamental design for a pencil lead testing machine, as shown.

CARL J. ESSMANN,
